FLOOR TREATING MECHANISM

Albert E. Moorhead, Oakland, Calif., assignor to
 Moorhead Development Co., Inc., Oakland,
 Calif., a corporation of Nevada

Application August 16, 1932, Serial No. 629,039

15 Claims. (Cl. 91—48)

This invention relates to a mechanism for treating floors; such for example, as finishing and polishing floors, whether wood or linoleum, or the like.

5 For finishing floors, it is customary to utilize an appliance that incorporates an abrasive material, such as sand paper. This appliance is operated by hand power, or it can be driven as by an electric motor. In the latter case, the sand paper is usually wound around a roll which is rapidly rotated by the motor and is pressed against the surface to be finished.

10 For polishing floors, a similar arrangement is used, except that a polishing medium, such as wax or oil, is used in place of the abrasive; and often a buffing operation is added after the application of the polishing medium. In polishing and buffing, soft rolls can be used, overlaid with a layer of fabric or felt, which can be impregnated with wax or oil for the polishing operation.

15 It is one of the objects of my invention to provide a floor polisher and finisher that can be conveniently manipulated to replace the treating rolls, or to introduce new material over the rolls.

It is another object of my invention to improve the construction and operation of such floor polishers or finishers.

20 Floors to be polished or buffed are apt to have slight irregularities, such as bumps and depressions. If a polishing or buffing roll is merely urged against such a floor, the result may well be that only the high spots are effectively treated. By the aid of my invention, I provide a polishing or buffing action which ensures that even the depressions are treated. This is accomplished by providing a rather heavy but yielding layer over the body of the roll, which is expanded by centrifugal pressure when the roll is rotated, so 25 as to be urged yieldingly against all surfaces of the floor.

It is another object of my invention to provide a floor polisher or buffer in which the polishing or buffing medium can be quickly and easily renewed over the roll; as for example, by making the interior of the roll hollow to accommodate a supply roll.

25 It is still another object of my invention to provide a resilient supporting layer, of considerable mass, around the roll of such an apparatus, over which the treating layer can be disposed, and arranged in such a way that the supporting layer is urged outwardly by centrifugal force, so 30 as to leave an air space between this layer and

the roll. In this way, a full floating resilient treating layer is obtained.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of 5 my invention; but it is to be understood that this detailed description is not to be taken in a limiting sense, since the scope of my invention is best defined by the appended claims.

Referring to the drawings:

Figure 1 is a side elevation of a floor treating head incorporating my invention;

Fig. 2 is a front elevation thereof;

Fig. 3 is a perspective view of the head, showing the cover for the frame open, and one of the 20 side supporting members swung out, to illustrate the manner in which the roll structures can be removed from and replaced in the apparatus;

Fig. 4 is a partial sectional view taken along the plane 4—4 of Fig. 2;

Fig. 5 is a partial sectional view taken along the plane 5—5 of Fig. 1;

Fig. 6 is a detail sectional view transverse to the axis of one of the rolls, and along plane 6—6 of Fig. 2;

Fig. 7 is a perspective view of the hollow cylinder and its cover for accommodating the supply roll of treating material;

Fig. 8 is a fragmentary perspective view of the supporting layer and its attaching means, 35 which layer is adapted to be wound around the outside of the hollow cylinder;

Fig. 9 is a perspective view of a supply roll of treating material adapted to be accommodated inside of the hollow cylinder shown in Fig. 7;

Fig. 10 is a view similar to Fig. 6, but showing the manner in which the centrifugal force acts to provide a floating contact between the floor and the treating material; and

Fig. 11 is a view similar to Fig. 10, showing 45 how an abrasive layer may be used on the roll structure.

The floor treating device is shown in Figs. 1, 2, 4, 5, 6 and 10, as disposed for movement over a floor surface 11 to be treated. In the present 50 instance the device is intended to be propelled manually as by a forked handle 12 (Figs. 1 and 2) pivoted as by screws 13 to the motor casing. This motor casing houses a motor intended to supply the motive power for a pair of axially 55

aligned roll structures shown generally at 15 and 16.

Both roll structures 15 and 16 are arranged in a frame shown generally at 17 (Figs. 1, 2 and 3) and are mounted on an axis transverse to the direction in which the floor treating head is moved by the handle 12. The frame 17 and the motor frame 14 are preferably in releasable engagement as shown most clearly in Fig. 4, whereby it is possible to replace one type of floor treating head with another. For example, a vacuum cleaner head can be substituted for the frame 17 and its associated parts. However, since the structure permitting this interchangeability has been described and claimed in my prior Patent No. 1,854,214 granted on April 19, 1932 and entitled Floor cleaning appliance, it is considered unnecessary to describe this feature further. In general, however, it may be stated that there are telescoping flanges 18 and 19 (Fig. 4) between the motor frame 14 and the floor treating frame 17.

In order to make it possible to roll the organization 14-17 on the floor 11, use is made of several supporting rollers; one roller, such as 20 (Fig. 1) is mounted in a roller support 21 at the rear of the frame 14 as by being pivoted on a screw 22. A pair of side rollers 23 are supported at the rear of the frame 17 forming a three-point support for the device.

Since the treating roll structures 15-16 are disposed on an axis in advance of the axis of the supporting rollers 23, it is apparent that the adjustment of the axis of these roll structures with respect to its height above the floor 11, can be accomplished by tilting the organization 14-17 about the axis of rolls 23. This tilting in turn can be performed by varying the relative position of the roller support 21 with respect to the motor casing or frame 14, and it is for this purpose that this support 21 is pivotally mounted on frame 14. This relative position can be varied by the aid of the foot of the operator disposed on top of the support 21 for tilting it either in a clockwise or a counterclockwise direction about the axis of roller 20. A clockwise tilt will obviously raise the rear of frame 14 and correspondingly lower the roll structures 15-16. A counterclockwise motion of the support 21 about the axis of roller 20 will, however, lower the rear of frame 14 and will raise the roll structures 15-16. Several notches, such as 24, can be provided in an arcuate portion of the support 21 (Fig. 1) cooperating with a spring pressed button 25 on frame 14, for keeping the support 21 in any of the adjusted positions, by engaging in one of the notches.

The lowered portion of the roll structures is indicated in Fig. 6 and a raised portion is indicated in Fig. 10.

There will now be described the transmission mechanism between shaft 26 (Fig. 4) operated by the motor in frame 14, and shafts 27 and 28 (Fig. 5) to which the roll structures 15 and 16 are coupled.

Frame 17 has a central wall-like portion 29 (Figs. 3, 4 and 5). This portion has a cavity 30 in the rear in which can be disposed ball bearing structures 31 and 32 for shaft 26. The axis of this shaft is coincident with the axis of the motor and is detachably coupled thereto by appropriate mechanism as disclosed in my prior patent above referred to. This shaft carries a pinion gear 34 meshing with a gear 35 fastened to a shaft 36 as by the aid of a hub 37 secured to the gear. If desired, gear 35 can be made from some non-metallic material to reduce noise. Shaft 36 can

be supported in ball bearings 38 and 39 carried by the center wall 29.

The front end of shaft 36 extends into a cavity 40 (Figs. 4 and 5) and carries a bevel gear 41. This bevel gear in turn meshes with the bevel gears 42 and 43 respectively supported on the roll structure driving shafts 27 and 28. These shafts are shown in Fig. 5 as mounted for rotation in the side walls of the cavity 40 by the aid of ball bearing structures 44 and 45. It is apparent that due to this drive, roll structures 15 and 16 are rotated in opposite directions but on a common axis. In this way any tendency for the floor treating device to move either forwards or backwards due to the traction of these rolls 15 is obviated.

Since it may be desirable to provide oil, grease or other lubricant in cavities 34 and 40, a fluid-tight envelope is provided for these cavities. Thus the rear wall 46 (Fig. 4) of frame 17 closes these cavities at the rear. Where shafts 27 and 28 project out of the center wall 29, as shown in Fig. 5, use can be made of a felt washer 47, held in place as by a metal washer 48. The felt washer 47 and the metal washer 48 are disposed on the outside of the center wall 17 and the felt washer 47 is in contact with the shaft 27.

The ratio of reduction is such that rotation of shafts 27 and 28 is provided at about the rate of 1000 revolutions per minute, in order to utilize the effects of centrifugal force. In order to facilitate assembly and repairs, the center wall 29 is shown as split as at 50 (Figs. 3 and 4), the two parts being joined together in any appropriate manner. A transverse bumper bar 51 is fastened to the lower portion of the wall 29 and can carry a rubber bumper 52. All this is most clearly shown in Fig. 3.

From the center wall 29 there extend rear walls 53 and 54. These rear walls are shown most clearly in Figs. 6 and 10. For a short distance these rear walls are extended upwardly in an arc about the axis of the roll structures 15 and 16. Furthermore, side members 55 and 56 (Figs. 3 and 5) are provided for closing the ends of the frame. A cover member 57 is pivoted to the center wall 29 as on the studs 58 and completes with the rear walls 53 and 54, a partial hollow cylindrical housing for the roll structures 15 and 16. As shown most clearly in Fig. 5, this cover member has a flange 59 at each end overlying the side walls 55 and 56 and contacting therewith. Furthermore, the front lip 60 (Figs. 3, 4 and 6) is in contact with the top of the bumper bar 51.

The cover 57 can be held in its closed position by a spring pressed manually controlled button 61 which engages in a cavity 62 in the central wall 29. This button 61 has a shaft 63 extending through the front wall of the cover 57 and carrying the knob 64 for manual control. A spring 65 is disposed around the shaft 63 and contacts at one side with the end of a bushing 66 for the shaft 63; and at its other end it engages the knob or button 61 to urge it toward the right as viewed in Fig. 4.

In order to facilitate carrying the entire floor treating device, a bail 67 (Figs. 1, 2, 4, and 5) can be pivoted on the screws 58.

Hemi-spherical bumpers 68 can be provided on the exterior surface of the side members 55 and 56 as indicated in Figs. 1, 2, and 5.

The roll structure can be best described in connection with Figs. 7, 8, and 9. Each of these structures includes a metallic cylinder 49, and each of these cylinders has an integral end wall 75

69. This end wall is provided with a recess 70 in which the end of shaft 27 or 28 respectively can be accommodated. Each of these shafts is provided with a diametric bar 71 serving as a driving element of a detachable connection. The recess 70 in the end wall 69 has a corresponding non-circular space for accommodating the member 71, whereby the cylinder 49 is driven.

5 In the present instance cylinder 49 is shown as 10 hollow and as having an end cover 72. This end cover has a shoulder 73 cooperating with a reduced flange on the cylinder 49.

15 The side plates 55 and 56 are provided with rotatable supports for the roll structures 15 and 16, whereby any whipping action of the rolls during the period of rotation is obviated by steadyng the rotating structures. Thus for example, as 20 shown most clearly in Fig. 5, the side 55 has a recess 74 in which is accommodate a ball bearing structure 75. On this ball bearing structure is 25 rotatably mounted a conical support 76, cooperat- ing with a conical recess 77 in the cover 72. In order to urge the entire roll structure toward the 30 rotatable conical support 76, use is made of a re-entrant central portion 78 of cylinder 49, coaxial with shaft 27. This portion 78 can be hollow for the accommodation of a compression spring 79. A ball 80 can be interposed between this com- 35 pression spring and the bar 71 of shaft 27. It is apparent that this compression spring 79 acts to urge the entire roll structure 16 toward the left; that is, on to the conical support 76.

40 To facilitate removal and replacement of the roll structures 15 and 16, each of the side mem- bers 55 and 56 is removable. This is shown most 45 clearly in Figs. 1 and 3. It is there seen that each side member is pivotally mounted as by a pin 81 on a corresponding back member 53 or 54. Near the front edge of each of these side 50 members 55 and 56 is a projection 82 arranged to enter into a corresponding slot 83 in the front bar 51. In order to hold the side members 55-56 in closed position, a pin 84 (Fig. 3) can be used having a head 85 which can be accommo- 55 dated in a hollow 86 in the exposed surface of the side member 55 or 56.

55 It is apparent that the apparatus so far de- 60 scribed makes it possible, by removing pins 84 and a retraction of the button 61, to open up the en- tire frame as indicated in Fig. 3.

65 Located within each of the hollow cylinders 49 is a supply roll 87 (Figs. 5, 6, 9, 10). This supply roll can be impregnated with wax or oil or other media; or it may be a roll of sand paper or emery cloth. The roll is held in central position by the reentrant portion 78 of the end wall 69 and on the projection 88 extending from the cover member 72. The free end of the roll can extend through a slot 89 in the cylinder, and can be wrapped around a heavy layer fastened to the outside of the cylinder 49. This heavy layer is shown in this instance in Fig. 8 and comprises a base layer 90 of some heavy material, such as rubber; and a thick superimposed layer 91 of some soft or resilient fabric, such as felt. These two layers can be cemented or glued together and can be of such a length that it extends approxi- 70 mately only once around the periphery of cylinder 49. It is attached at only one of its ends to the cylinder 49, and preferably at an edge of the slot 89. For this purpose a U-shaped support 92 is provided, to which the layer 90-91 is fastened. The legs of this support engage the inner and outer surface of the cylindrical wall of cylinder 49 and joined to it as by riveting or

other appropriate means. As shown most clearly in Figs. 6 and 10, the free end of the supply roll 87 is led through the slot 89 and overlies the layer 90-91. A definite length of this treating material is fed through slot 89, and is anchored at 5 one end, as by the aid of a series of prongs or projections 93 extending from the lower edge of member 92, which projections can engage the material 87. It may be possible to omit prongs 93, since the friction between material 87 and 10 pad 91 may be sufficient to maintain it against further unwinding. When the exposed material wound over the layer 90-91 is worn out or too soiled for further use, it can be unwound and 15 disengaged from the prongs 93. Then it can be pulled further out from the slot 88 and the used portion cut off. A new and clean portion can then be unwound from roll 87 and anchored to the projections 93 as heretofore stated.

20 The rotation of the roll structures by the aid of the motor in housing 14 is such that the free end of the composite material 90-91-87 is thrown out by centrifugal force; and if the roll structures are raised sufficiently above the floor 11, as in Fig. 10, a floating contact is secured. In 25 this figure it is clear that there is an air space 94 between this composite layer and the floor 11, providing the floating effect. A whipping action is produced by centrifugal force, acting on the unattached ends of the layer 90-91-87. 30 This serves the purpose of beating or driving in, to any slight depression or hollow in the floor surface 11, the treating material carried by the 35 member 87.

Of course the direction of rotation as indicated by arrow 95 of Figs. 6 and 10 is in conformity with the direction in which the composite layer is wound over the cylinder 49. A definite limit is imposed upon the degree to which a centrifugal force can throw out the free end of this composite 40 layer, by the inner walls of bar 51, cover 57, and rear walls 53, 54. In order to ensure against wear, these parts can be lined with good wearing material, such as indicated at 96, 97, and 98 (Figs. 3 and 6). These can be detachably held 45 to the inner surfaces of these members by screws 99, making it possible to replace worn out wear plates.

50 Since the contact between the treating member 87 and the floor is fully floating, it is also apparent that it can accommodate itself easily to irregularities, such as bumps, without producing an undue strain upon the driving mechanisms.

Furthermore, since centrifugal force is used to 55 urge the material from roll 87 outward to provide the air space 95, it is apparent that it is unnecessary to adjust the height of the roll structures above the floor. The pad and its medium is driven toward the floor by centrifugal force. All shocks are eliminated from the mechanism 60 due to the floating air support.

When an abrasive treating material is to be used, the mode of overlying the pad structure 90-91 is preferably such as illustrated in Fig. 11. In this form, roll 100 represents a roll of sand- 65 paper or the like. It is unwound through slot 89 for a length slightly greater than the periphery of cylinder 16, and the unwound portion is doubled back in a clockwise direction over the pad 90-91. Its free end is reentrant into slot 89, and 70 is anchored on prongs 93. An air space 101 exists between the cylinder 16 and the treating medium. However, since the end of material 100 is anchored on the prongs 93, the centrifugal force 75 cannot act to throw the material against the wear 75

plates 97, 98, thereby saving such plates from unnecessary abrasion. The effect is to provide a yielding, eccentric cylindrical treating surface, of a diameter and eccentricity insufficient to reach these plates 97, 98.

In this mode of use, all of the above mentioned advantages of a full floating contact are retained.

I claim:

10. 1. In a floor treating device, a frame having side members, a front member, and a back member, a cover detachably supported on the frame, one of the side members being pivotally mounted on the back member, a roll structure, and means 15 for rotatably supporting said structure in the side members, the said means in the pivotally mounted side member being in the form of a stub shaft mounted for free rotation and disengageable from the roll structure when said pivotally mounted member is opened on its pivot.
20. 2. In a floor treating device, a frame having side members, a front member, and a back member, a cover detachably supported on the frame, one of the side members being pivotally mounted 25 on the back member, a roll structure, and means for rotatably supporting said structure in the side members, the said means in the pivotally mounted side member being in the form of a conical support engaging a conical socket in the 30 roll structure, and mounted for free rotation in the said pivotally mounted side member.
3. In a floor treating device, a roll structure, a frame in which said structure is accommodated, said frame having a pair of side members respectively adjacent opposite ends of said roll structure, a drive shaft journalled in one side member having a detachable driving connection with said roll structure, the other side member being removable from its supporting position to 40 facilitate removal and replacement of the roll structure, a rotatably mounted conical support for the roll structure on said other side member, and resilient means supported by the roll structure, urging said structure toward the conical support.
4. In a floor treating device, a roll structure, a frame in which said structure is accommodated, said frame having a pair of side members respectively adjacent opposite ends of said roll structure, a drive shaft journalled in one side member having a detachable driving connection with said roll structure, the other side member being removable from its supporting position to 50 facilitate removal and replacement of the roll structure, a rotatably mounted conical support for the roll structure on said other side member, resilient means supported by the roll structure, urging said structure toward the conical support, and a removable cover member above the roll structure and supported on the frame.
5. In a floor treating device, a pair of roll structures, a frame having a center portion disposed between the roll structures, a pair of drive shafts journalled in said center portion and extending in opposite directions, for respectively driving the roll structures, each of said drive shafts having a detachable driving connection with its respective roll structure, said frame also having pivotally mounted members, respectively adjacent the other ends of the roll structures, to 65 facilitate removal and replacement of the roll structures, a rotatably mounted conical support on each of said pivotally mounted members for the roll structure, resilient means supported on each roll structure, urging said structure toward 70
- 75

the conical support, and a cover member above both roll structures and pivotally mounted on said center portion.

6. A floor polishing roll structure, comprising a cylinder, a resilient layer that is adapted to contact the floor for imparting a polish thereto, said layer overlying the cylinder and being at least partly in contact with the periphery of the cylinder, and means for attaching one end only of the layer to the cylinder, the remainder of the layer being unattached, said layer being of such length that it envelops the cylinder approximately once, said layer comprising a heavy base portion and a yielding fabric extending therewith.

7. A floor polishing roll structure, comprising a cylinder, a resilient layer that is adapted to contact the floor for imparting a polish thereto, said layer overlying the cylinder, and means for attaching one end only of the layer to the cylinder, the remainder of the layer being unattached, said layer being of such length that it envelops the cylinder approximately once; said layer comprising a heavy rubber base portion and a felt fabric extending therewith.

8. In floor treating apparatus, a hollow cylinder having a slot at its periphery, means for holding a roll of floor treating material in the cylinder, and means for anchoring a length of said material when unwound through the slot, 30 to the cylinder, comprising a series of pointed members arranged along the edge of the slot.

9. In floor treating apparatus, a hollow cylinder having a slot at its periphery, means for holding a roll of floor treating material in the cylinder, permitting the roll to be unwound through the slot, and a resilient layer overlying the cylinder and beneath the length of floor treating material, said resilient layer being attached at one end only to the cylinder, adjacent an edge of the slot, and being of such length that it envelops the cylinder approximately once.

10. The combination as set forth in claim 9, in which the resilient layer comprises a heavy rubber base portion, and a felt fabric extending thereover.

11. In floor treating apparatus, a hollow cylinder having a slot at its periphery, means for holding a roll of floor treating material in the cylinder, means for anchoring a length of said material when unwound through the slot, to the cylinder, a resilient layer overlying the cylinder and beneath the length of floor treating material, said resilient layer being attached at one end only to the cylinder, adjacent an edge of the slot, and being of such length that it envelops the cylinder approximately once, said anchoring means comprising a series of pointed members arranged along the edge of the slot.

12. A floor treating device, comprising a rotatable member, and a resilient non-abrasive treating element encompassing the member and fastened at one end only to the member to cause the free end of said element to move outwardly under the influence of centrifugal force.

13. A floor treating device, comprising a rotatable member, a resilient treating element encompassing the member and fastened at one end only to the member to permit the free end of said element to move outwardly under the influence of centrifugal force, and means whereby the outward motion of said free end is limited.

14. A floor treating device comprising a rotatable member, a resilient treating element encompassing the member and fastened at one end

only to the member to permit the free end of said element to move outwardly under the influence of centrifugal force, and means forming a casing surrounding a portion of the rotatable member, and restraining said treating element to an arcuate configuration during rotation of the rotatable member.

15. A floor treating device comprising a rotatable member, and a resilient treating element

fastened at each end to the member and encompassing the member, said resilient treating element having a length greater than that sufficient to encompass the rotatable member whereby an eccentric effect is secured through the action of 5 the centrifugal force produced by the resilient treating member.

ALBERT E. MOORHEAD.
